WIDE BAND AMPLIFIER

Winfield R. Koch, Haddonfield, N. J., assignor to
 Radio Corporation of America, a corporation of
 Delaware

Application February 29, 1940, Serial No. 321,543

5 Claims. (Cl. 179—171)

The present invention relates to wide band high frequency amplifiers, and has for an object to provide an improved wide band amplifier and means therein for maintaining the selectivity characteristic or band width substantially constant with variations in the volume control adjustment thereof.

It is known that variations in the biasing potential of an amplifier for volume control purposes tend to change the input loading caused by the grid of the tube, the loading being greater the higher the frequency at which the amplifier operates, and increasing as the bias potential is decreased.

It has been found that the loading of a signal conveying circuit such as a signal input grid circuit is caused partly by the electron transit time and partly by the inductance of the cathode lead at high and ultra high frequencies, and it is a further object of the present invention, to provide an improved amplifier having a tuning network in one or more of the stages thereof for compensating the cathode lead inductance in such a manner that the loading of the input circuit may be made substantially uniform over a relatively wide frequency band and may provide additional compensation for the transit time of the electrons.

By the use of the present invention, a multi-stage ultra high frequency amplifier may be provided with volume control involving grid bias variation, from AVC means, for example, without changing the effective loading of the input circuits of the various stages thereof when operating over a relatively wide band of signal frequencies.

The invention will be better understood from the following description when considered in connection with the accompanying drawing and its scope is pointed out in the appended claims.

In the drawing,

Figure 1 is a schematic circuit diagram of a high frequency wide band amplifier embodying the invention; and

Figure 2 is a similar schematic circuit diagram of the amplifier of Figure 1 embodying a modification of the invention.

Referring to Fig. 1, 5 is one of a series of amplifier stages in a signal amplifying system to which it is coupled through suitable tuned input and output transformers 6 and 7 respectively and, in the present example, may be considered as the video signal amplifier of a television receiver, and being tuned to a relatively wide pass band of signal frequencies.

5 The amplifier stage includes a suitable amplifier tube 8 having a signal input grid 9 connected with a high impedance tuned input circuit 10 formed by the secondary 11 of the transformer 6 and a shunt capacity provided by a capacitor 12. A limiting resistor 13 is provided across the tuned input circuit which is connected at its low potential side to a variable source of biasing potential 14 through a filter resistor 15.

10 The cathode inductance or the inductance of the cathode lead is indicated as a unit element 16 connected between the cathode 17 and a connection with ground 18 through a filter resistor 19.

15 In the present example, the biasing potential source is a potentiometer or bleeder resistor 14 connected to ground and across which there is provided a suitable biasing potential having a polarity as indicated.

20 By connecting a low pass filter structure or network, which includes the cathode lead inductance, as an impedance between the cathode and ground, the cathode circuit may be made effectively resistive in the pass band of the amplifier uniformly throughout the pass band. Such a network is shown in the present example and comprises the cathode lead or other inherent inductance 16 in the cathode circuit, a second tuning inductance 20, and a series tuning capacitor 21. The grid bias supply to the grid 9 is suitably filtered by the resistor 15 in conjunction with a by-pass capacitor 22. The filter resistor 19 is effectively the output resistor of the low pass filter structure.

25 In a wide band amplifier, for example, one amplifying uniform signal frequencies between 19 and 31 megacycles, the loading of the input circuit 10 because of the grid 9 of the amplifier tube 8, is considerably greater for the upper end of the band than for the lower end thereof. At normal bias, this may be compensated by slight changes in the tuning of the system, that is, the tuning of the circuit 10, so that a flat response will result or a uniform gain will be provided throughout the pass band of the amplifier.

30 However, if the biasing potential on the amplifier tube is required to be varied for volume control purposes, as by adjustment of the contact 14, the equivalent shunt resistance offered by the grid of the tube will increase as the bias on the tube is increased and the change in loading will be greater at the high frequency end of the band and the selectivity characteristic will tend to rise at the high frequency end of the band. This is for the reason that inductance in the cathode lead 35 or in the cathode has the effect on the grid cir-

cult of a shunt resistance which varies with frequency and bias. In the present example, the upper limit of this resistance is determined by the resistor 18 which may be set, for example, at 500 ohms.

The reactance of the cathode circuit increases with frequency and thus increases the effective shunt resistance across the grid circuit, the value varying inversely as the square of the frequency. This may be of the order of 20,000 ohms at the upper limit of the band hereinbefore referred to, such as 31 megacycles, and may be 100,000 ohms at the lower end of said band, such as 19 megacycles.

In accordance with the invention, the effective loading of the input circuit is maintained substantially uniform with changes in bias control by means of the low pass filter structure or network provided in the cathode circuit which has, in the present example, a cut-off above 31 megacycles, whereby the cathode circuit is made effectively resistive throughout the band. While the variation in biasing potential under such conditions tends to cause some changes in the loading the minimum is relatively high, such as 100,000 ohms. Therefore, it has little effect upon the circuit which has a relatively low resistance of a few hundred ohms in a wide band amplifier.

Referring to Fig. 2, wherein like reference numerals are applied to the same circuits and elements as in Fig. 1, the cathode circuit is modified to include in series therewith, a shunt tuned inductance 25 and capacity 26, bypassed to ground by a capacitor 24 together with a variable biasing potential source comprising bleeder resistors 27 and 28. The resistor 28 is variable to control the flow of current from a positive terminal 29 to ground 30, thereby to develop a biasing potential across the resistor section 27 for the grid. The bias potential is supplemented by a variable AVC potential applied to the grid from a supply lead 31 across a grid resistor 32, the latter being connected in series between the low potential side of the tuned input circuit 10 and ground 30. Since the operation and purpose of this circuit is otherwise the same as in Fig. 1, further detailed description is unnecessary.

For the variable biasing potential on the control grid 8, from either the variable source 27 or the AVC source 31, the band pass characteristic of the amplifier and the uniform amplification of signals therein is substantially unchanged, so that effective AVC control may be obtained without undesired loading effects.

I claim as my invention:

1. In a wide band signal amplifier for high frequency signals, the combination of an amplifier tube having a cathode and a cathode lead, a signal input circuit therefor, a signal output circuit therefor, and means for compensating the cathode lead inductance of said tube comprising a low pass filter network in circuit with the cathode and including the cathode lead inductance.

5 2. In a wide band high frequency signal amplifier, the combination with an amplifier tube having a signal input grid, a cathode and a cathode lead, of means providing a signal input circuit connected between said grid and cathode through said lead, means for applying a variable biasing potential between said grid and cathode, thereby to vary the gain of said amplifier, and means for preventing the cathode lead inductance of the said tube from affecting the uniform signal amplification of said amplifier over the frequency band thereof, comprising a low pass filter network including the cathode lead inductance, connected as an impedance in circuit between said cathode and ground.

10 3. In a wide band signal amplifier for high frequency signals, the combination with an amplifier stage therein comprising a tuned input grid circuit, means for varying the grid bias effective on said stage for volume control thereof, a cathode circuit, and means for causing the cathode circuit to be effectively resistive in the pass band of the amplifier substantially uniformly throughout the pass band, comprising a low pass filter network in said cathode circuit 15 including a predetermined inductance inherent in said circuit, said filter network having a cut-off frequency above the pass band of the amplifier.

20 4. In a wide band, high frequency amplifier comprising a plurality of amplifier stages, the combination with at least one of said stages of means providing a tuned input grid circuit, means for applying a variable biasing potential to said circuit for effecting volume control of said amplifier stage, a cathode circuit for said stage having a predetermined inherent inductance in operation effective to cause a variation of the input grid circuit loading with variations in frequency and in biasing potential, and means for minimizing the effect of said inductance on the loading of said circuit comprising a low pass filter network including said inductance and a filter resistor as the output element thereof in said cathode circuit, said filter network having a cut-off frequency above the operating frequency band of the amplifier.

25 5. In a high frequency wide band amplifier, the combination of an amplifier stage comprising a tube having a cathode, and a cathode lead which is effective as an inductance at the operating frequency of the amplifier, means for applying a varying biasing potential to said stage for controlling the volume level of amplified signals, and means for maintaining the effective shunt loading of said input circuit relatively high with respect to the effective resistance of said circuit with variations in biasing potential, comprising a low pass filter network in circuit with the cathode and including the cathode lead inductance, said network having a cut-off frequency above the pass band of the amplifier, thereby to cause said cathode circuit to be effectively resistive in said pass band of the amplifier.
